UNITED STATES PATENT OFFICE.

RUFUS D. BRADDY, OF ANACONDA, MONTANA.

SHADE-BRACKET.

1,192,847.

Specification of Letters Patent.

Patented Aug. 1, 1916.

Application filed February 18, 1916. Serial No. 79,190.

To all whom it may concern:

Be it known that I, RUFUS D. BRADDY, a citizen of the United States, residing at Anaconda, in the county of Deerlodge and 5 State of Montana, have invented new and useful Improvements in Shade-Brackets, of which the following is a specification.

Broadly stated, this invention contemplates the provision of means for hanging 10 window shades and curtains without the use of nails, screws or the like, thereby avoiding damage to the window casing by use of such elements.

The nature and advantages of the invention will be better understood, when the following description is read in connection 15 with the accompanying drawing, the invention residing in the novel combination, construction and arrangement of parts hereinafter claimed.

In the drawing forming part of this specification like numerals of reference indicate similar parts in the several views and wherein:

25 Figure 1 is a front elevation showing the application of the device. Fig. 2 is a top plan view. Fig. 3 is a sectional view taken on line 3—3 of Fig. 1. Fig. 4 is a detail view of one of the clamps. Fig. 5 is a detail view 30 of one of the shade brackets.

Referring more particularly to the drawing 10 indicates a curtain pole, which may be constructed of any suitable material and of any desired length, and upon which the 35 lace curtain is adapted to be secured in any suitable manner.

In carrying out my invention use is made 40 of the clamps generally indicated at A, one of these clamps being arranged at each side of the window casing B as shown. Each of 45 these clamps preferably consists of relatively movable companion members 11 provided at one end with a suitable opening for the reception of the pole 10, and upon which the 50 said members are mounted for longitudinal adjustment thereon. The members 11 are fixed relatively to the pole, in any adjusted 55 position by means of the set screws 12 carried by the respective members and adapted to engage the pole 10. The opposite ends of the members terminate to provide the lugs 13 disposed in confronting 60 relation and adapted to engage the opposite sides of the window casing B in the manner shown in the drawing, for the purpose of properly supporting the pole 10. Each of

the lugs 13 is provided with a rubber foot 14, but this member may be constructed from leather or other suitable material to obviate marring the window casing B, which generally results from the use of nails, screws or analogous fastening elements. Passed 60 loosely through one of the members 11 of each clamp, and threadedly associated with the other of said members, is a thumb screw 65 15 by means of which the members are adjusted relatively and held in gripping relation upon the window casing as illustrated. By reason of the fact that the clamps in their entirety are adjustable longitudinally 70 of the pole 10, it is manifest that the entire device may accommodate itself to windows of varying widths.

In connection with the construction hereinabove described I employ window shade 75 brackets 16 pivotally mounted upon the pole 10, and preferably positioned between the members 11 of each clamp. The body portion of the bracket is formed to provide a lateral extension 17 to the free end of which 80 a pad 18 of any suitable material is secured to prevent marring of the window casing, it of course being understood that when the brackets are operatively positioned the extension 18 bears against the window casing 85 at a point immediately beneath the clamps A, thereby relieving the latter of undue strain under the weight of the various parts supported thereby. The brackets 16 are also adapted to be held in fixed position with 90 relation to the pole by means of set screws 19, and are provided with suitable openings 20 for the reception of the opposite ends of the shade roller. By reason of the fact that 95 brackets are positioned between the respective members of the clamps, it is manifest that by merely loosening the set screws 12 and 19 the clamp and its associated bracket may be adjusted as a unit longitudinally 100 upon the pole 10 to accommodate windows of varying widths.

It is to be borne in mind that the device herein shown and described is merely illustrative of one embodiment of the invention, 105 to which I do not limit myself, and that various changes may be resorted to when desired as fall within the scope of what is claimed.

What is claimed is:

1. A combination curtain pole brace and 110 shade bracket comprising a member freely pivoted upon the pole and mounted for lon-

itudinal adjustment thereon, and means for holding the member fixed relatively to the pole.

2. A combined curtain and window shade hanger comprising a curtain pole, a clamp comprising pairs of members mounted upon the pole and adapted to clamp on the window casing, means connecting said members and operable to adjust the latter into clamping relation, means for holding said members fixed relatively to the pole, a curtain shade bracket freely pivoted upon the pole and adapted to bear against the window casing, and means for holding said bracket fixed in its adjusted position.
3. A combined curtain and window shade hanger comprising a curtain pole, companion relatively movable clamping members

mounted upon the pole for longitudinal adjustment and adapted to be clamped on the window casing, means for holding said members in gripping relation, a curtain shade bracket pivotally associated with the pole and fitted between said members for adjustment therewith longitudinally of said pole, said bracket being adapted to bear against said window casing immediately beneath said clamps, and means for holding said bracket fixed relatively to said pole.

In testimony whereof I affix my signature in presence of two witnesses.

RUFUS D. BRADDY.
